UNITED STATES PATENT OFFICE.

EDGAR J. HICKS, OF INDIANAPOLIS, INDIANA.

SAW-JOUNTER.

SPECIFICATION forming part of Letters Patent No. 731,901, dated June 23, 1903.

Application filed March 30, 1903. Serial No. 150,241. (No model.)

To all whom it may concern:

Be it known that I, EDGAR J. HICKS, a citizen of the United States, residing at Indianapolis, in the county of Marion and State of Indiana, have invented certain new and useful Improvements in Saw-Jounters, of which the following is a specification.

My said invention consists in various improvements in the details of construction and arrangement of the parts of a combined saw jointer and gage of that general character shown in my former patent, No. 624,332, of May 2, 1899, all as will be hereinafter more fully described and claimed.

Referring to the accompanying drawings, which are made a part hereof, and on which similar reference characters indicate similar parts, Figure 1 is a front elevation of a combined saw jointer and gage embodying my said improvements; Fig. 2, a similar view of the central portion thereof, showing the clamping-plate in the reverse position; Fig. 3, a view similar to Fig. 2 with the clamping-plate and operating-cam removed; Fig. 4, a central vertical section on the dotted line 4-4 in Fig. 2; Fig. 5, a perspective view of the clamping-plate, and Fig. 6 a similar view of the gage-plate.

In said drawings the portion marked A represents the base block or frame, B the gage-plate, and C the clamping-plate.

The base block or frame A is of substantially the form shown in said former patent, consisting of a suitable casting having ribs 1 and 2 and projecting points 3 on its front face, also vertical ribs 4, extending between ribs 1 and 2, in which are formed shoulders 5 near their upper ends to serve as rests for the upper edge of the file when clamped in its flat position. The upper edge of the block is formed with a central recess, as in said former patent. The gage-plate B is also of a well-known form, mounted in said central recess in frame A, being secured in position by means of a central screw b and supported at each end on a cone-shaped lug b'.

The clamping-plate C is mounted in a vertical way formed in the frame A and is adapted to slide vertically therein. It is retained in position by means of laterally-projecting wings c on its rear side and similar wings c'

on its front side near its top. The upper end of said plate forms the upper clamping-jaw, and a projecting lug c² near its lower edge forms the lower clamping-jaw. The lower portion of said clamping-plate is recessed on its rear side and formed with a curved shoulder c³, which rests upon an operating-cam C'. Said cam is mounted upon a cylindrical lug a, which projects from the face of the base-block at a suitable point. The clamping-plate C is put in place by extending its upper end through the way in the base-block and turning it to position, bringing the upper end thereof, with the projecting wings c', through the widened upper portion of said way. Said plate is then slid downwardly, with the wings c' on the other side. The screw b, provided for securing gage-plate B in position, is then screwed downwardly until the gage-plate is firmly seated in position, when the point of said screw will be in position to prevent the clamping-plate C from being raised to a point where the wings c' will clear the narrowed portions of the way in which said plate is mounted. Said plate is thus retained in position without the use of the retaining-screw used in the aforementioned Letters Patent, while it is permitted a free vertical adjustment.

In operation, it being desired to use a file in horizontal position as for jointing the points of the teeth, said file is placed flat-wise between the lugs 3 and the upper end of clamping-plate C, said clamping-plate being in the position shown in Fig. 1. The cam C' is then turned by means of its handle C⁴ until said file is firmly secured. When it is desired to use the file in a flat position, as when employed for jointing the sides of the teeth, it is placed with one edge resting against the shoulders 5 in the vertical ribs 4, and its other edge rests upon the lug c² on the lower end of the clamping-plate C, the parts being in the position shown in Fig. 1. The cam is then turned on its pivot to the position shown in Fig. 2, when said file will be firmly clamped to the base or frame and ready for use.

All reference to the top of the tool in the foregoing description relates to the drawing alone, as will be readily understood, the tool itself, strictly speaking, having no top.

Having thus fully described my said invention, what I claim as new, and desire to secure by Letters Patent, is—

1. In a saw-jointer, the combination of the base block or frame provided with a suitable way, and a clamping-plate for the file, mounted in said way and formed with wings on its opposite sides, which engage on opposite sides of said base block or frame, substantially as set forth.
2. In a saw-jointer, the combination of the base block or frame provided with rests for the file in its different positions, and formed with a central way for the clamping-plate, and said clamping-plate mounted to slide in said way, and formed with wings which project on each side of said base block or frame, said clamping-plate being provided with rests or jaws for engaging one side of the file in its several positions, substantially as set forth.
3. In a saw-jointer, the combination of the base block or frame with a vertical way for the clamping-plate, said way being widened at one end, the clamping-plate mounted in said way and formed with laterally-projecting wings on its opposite sides, said wings on one side being at one end and adapted to pass through said widened portion of said way, a set-screw for limiting the motion of said clamping-plate, and a cam for operating it, substantially as set forth.
4. In a saw-jointer, the combination of the base block or frame provided with the rests for the file in its different positions, a gage-plate secured therein by a screw, the clamping-plate mounted in a central vertical way formed in said base block or frame, said clamping-plate being formed with laterally-projecting wings for engaging opposite sides of said base block or frame, the wings upon one side being formed at its end and adapted to pass through a widened portion of said way, said screw being of a length so that its end will come in position to limit the movement of said clamping-plate after it is in operative position, and a cam for operating said clamping-plate, all substantially as set forth.
5. In a saw-jointer, the combination of the base block or frame provided with rests for the file in its different positions and with a central way, and a clamping-plate mounted to slide in said central way and formed with integral projections adapted to engage the sides of said way and retain said clamping-plate in place, substantially as set forth.

In witness whereof I have hereunto set my hand and seal, at Indianapolis, Indiana, this 23d day of March, A. D. 1903.
